STOCKING

Buddy Ontra, New York, N. Y., assignor of one-half to Vo-Jul Textiles, Inc., Doylestown, Pa., a corporation of Pennsylvania

Application July 2, 1949, Serial No. 3,666

Term of patent 14 years

(Cl. D47—7)

To all whom it may concern:

Be it known that I Buddy Ontra, a citizen of the United States, and a resident of New York, county of New York, State of New York, have invented a new, original, and ornamental Design for a Stocking, of which the following is a specification, reference being had to the accompanying drawings, forming a part thereof, wherein:

I claim:

The ornamental design for a stocking, as shown.

BUDDY ONTRA.
